UNITED STATES PATENT OFFICE

2,258,407

WIDE BAND ANTENNA

Philip S. Carter, Port Jefferson, N. Y., assignor to
 Radio Corporation of America, a corporation of
 Delaware

Application July 28, 1938, Serial No. 221,694

8 Claims. (Cl. 250—33)

The present invention relates to antennas and, more particularly, to antennas for use with wide band television transmission and reception.

The primary object of the present invention is to provide a highly directional antenna system which will have an extremely wide frequency band when connected to a transmission line of ordinary impedance characteristics. In other words, an object is to provide an antenna which when directly connected to a transmission line has a flat impedance versus frequency characteristic over a broad range as seen looking toward the antenna from the apparatus connected to the transmission line and which will be highly directional.

Another object is to provide a directive antenna which will require no impedance matching circuit between the antenna and the transmission line in order to match the surge impedance of the transmission line to the impedance of the antenna.

A V type directive antenna, such as disclosed in my prior Patent #1,974,387 patented September 18, 1934, has of itself a sufficiently broad tuning characteristic to give satisfactory transmission and reception over bands of frequencies such as used in television, but it has been found that when this type of antenna is matched to a transmission line in any of the known ways the tuning characteristic may be narrowed sufficiently to make the system too narrow for wide band television.

This difficulty is overcome and the foregoing objects achieved in accordance with the present invention by providing a multiple V antenna array, the component elements of which are arranged effectively in parallel and by connecting the ends of the V together and feeding the system from the apex of one of the V's. While the component elements of the multiple V antenna are effectively in parallel in that all of the elements radiate or receive in parallel, the wires of the element may be actually connected in series.

A better understanding of my invention will be had by referring to the following detailed description, which is accompanied by drawings, wherein Figures 1, 1a, 2, 2a illustrate the manner in which the currents in the individual wires of two forms of antennae combine to affect the distribution of the total current, which is shown in Figures 1b and 2b. Figure 3 illustrates a V antenna to which the principles of the foregoing figures have been applied in accordance with my invention, and Figures 4 and 5 illustrate the modifications of my invention.

The theory underlying the present invention will be given particularly with reference to Figure 1, and is similar to that given in my co-pending application, Serial #155,385 filed July 24, 1937 (RCA Docket #13,081). While the theory is believed to be an approximately correct explanation of the principles underlying the present invention, further investigation may lead to some modification of this theory. It is to be understood, of course, that the invention is independent of any theory which may be advanced to account for the results obtained.

Figure 1 shows in effect a double dipole comprising two half wave length conductors A and B of equal length, except for the break in the center of conductor B for connection to the transmission line TL which extends to a suitable transmitter or receiver (not shown). Conductors A and B are very closely spaced from one another, perhaps a distance of $\frac{1}{100}$ of a wave length and are electrically connected together at their extreme ends. The currents flowing in the two conductors will be in the same direction in space although in opposite directions within the antenna circuit due to phase reversal at the ends. The arrows indicate the direction of current flow in the conductors. Consequently, the arrangement will be almost identical in its radiation characteristic with that of a single wire half wave dipole antenna. With such close spacing the mutual impedance, that is, the coupling between the two conductors, is almost equal to the impedance of one wire. Assuming the total current in Figure 1 to be the same as in a single wire dipole, then the current in each of the wires A and B will be one-half the total current and the power in both examples will be equal. The effective resistance of the antenna of Figure 1, however, will be quadrupled due to the current in each of the wires A and B being one-half of the total current. It will thus be seen that the radiation resistance of the antenna shown in Figure 1 is equal to four times the radiation resistance of a single wire dipole without the use of any special impedance matching circuit between the antenna and the transmission line.

Figure 1a illustrates the current distribution in each of the conductors A and B of the antenna of Figure 1, while Figure 1b illustrates the total current of the antenna of Figure 1.

Figure 2 illustrates another embodiment of the double dipole arrangement of Figure 1 wherein the lengths of the conductors A and B are greater than one-half a wave length. In this particular instance the length of each conductor leg is equal

to an odd number of eighths of a wave length. This antenna system will give a higher impedance to the transmission line TL than does the system of Figure 1.

Figure 2a illustrates the current distribution in the individual wire conductors A and B of the modification of Figure 2 while Figure 2b illustrates the total current of the antenna of Figure 2. The current distributions of Figures 2a and 10 2b are theoretical assuming, of course, the presence of sine wave current distribution throughout the conductors.

Figure 3 illustrates the application of the principles heretofore set forth with regard to Figure 2 to a V type antenna with which a directional characteristic is obtained. The directional characteristic as determined by the included angle between the legs of the V follows the principles set forth in my prior Patent 15 #1,974,387, issued September 18, 1934.

A V type antenna, as shown in Figure 3, and having single wire legs, each equal in length to an odd number of eighths of the length of the operating wave, has a radiation resistance of approximately 200 ohms, but by the transformation action heretofore explained and obtained from folding the wires, as shown in Figure 3, the radiation resistance is increased to the vicinity of 400 ohms.

Figure 4 illustrates an arrangement similar to Figure 3, except that the length of each of the conductors from the center point to the extreme end in this modification is an integral number of half wave lengths, as shown in the figure by the term $n\lambda/2$. In this modification a break must be provided in the center of conductor A since, if conductor A were a continuous wire the currents in the two conductors would be equal and opposite and the radiation resistance would be negligibly small.

In Figure 5 I have shown a further modification of my invention which is desirable for use where it is necessary to have an antenna which is substantially aperiodic over a very wide frequency range. The length of the conductors is the same as in the arrangement of Figure 4. In this case a resistance is placed at the apex of the folded wires. If the resistance is given a value equal to the average surge impedance of the V antenna, the antenna will be substantially aperiodic over a very wide band of frequencies. In this modification we have a case of two travelling waves on adjacent conductors combining their radiation effect to obtain the equivalent of a single standing wave. The antenna of this figure is bi-directional along the axis of the V in spite of the travelling wave on the wires.

In the foregoing examples it has been assumed that the conductors of the multiple V antennae are all of the same diameter. This does not have to be the case, however, and, if desired, the conductors may have different diameters, particularly in cases where it is desired to depart above or below, from an even transformation ratio. When conductors of different diameters are employed in the antenna systems of the invention it will be found that the conductor of larger diameter will carry the larger current. The difference in the amount of current carried by the conductors results in a different transformation ratio from the case where the conductors are all of the same diameter. If the conductors, which are directly fed by the transmission line, are made to have a smaller conductor than the other conductor, or conductors, of the 70 75

antenna system, the transformation ratio will be larger than the ratio for an antenna having conductors of the same diameter and, by the same token, if the conductor of the antenna which is directly fed by the transmission line has the larger diameter than the other conductors of the antenna system, the transformation ratio will be less than that of a single antenna system wherein the conductors are all of the same diameter.

While I have particularly shown and described several forms of my invention, it is to be understood that my invention is not limited to the forms illustrated and described but modifications may be made within the scope of my invention.

I claim:

1. A directional antenna comprising a pair of linear conductors, said conductors being disposed at an angle other than 180° with respect to each other in a single plane, a transmission line connected to the adjacent ends of said conductors, a second pair of conductors similar and parallel to said first pair of conductors and so closely spaced therefrom that the mutual impedance between said conductors is substantially equal to the impedance of one of said conductors, means for connecting the corresponding remote ends of said first pair of conductors to the remote ends of said second pair of conductors so that corresponding conductors of each pair are effectively energized that radio frequency energy from said transmission line in a series relationship, each of said conductors being of a length including at least one-half the length of the operating wave, whereby there is minimized the existence of reflected waves on said transmission line which might disturb the radiation characteristics of said antenna conductors.

2. A directional antenna comprising a pair of linear conductors, said conductors being disposed at an angle other than 180° with respect to each other in a single horizontal plane, a transmission line connected to the adjacent ends of said conductors, a second pair of conductors similar and parallel to said first pair of conductors and so closely spaced therefrom that the mutual impedance between said conductors is substantially equal to the impedance of one of said conductors, means for connecting the remote ends of said first pair of conductors to the corresponding remote ends of said second pair of conductors so that corresponding conductors of each pair are effectively energized that radio frequency energy from said transmission line in a series relationship, each of said conductors being of a length including at least one-half the length of the operating wave, whereby there is minimized the existence of reflected waves on said transmission line which might disturb the radiation characteristics of said antenna conductors.

3. A directional antenna comprising a pair of linear conductors, said conductors being disposed at an angle other than 180° with respect to each other and being located in a single horizontal plane there being a predetermined relation between the lengths of the conductors and the included angle, a transmission line connected to the adjacent ends of said conductors, a second pair of conductors similar and parallel to said first pair of conductors and closely spaced therefrom in the same horizontal plane, the spacing being such that the mutual impedance between said conductors is substantially equal to the impedance of one of said conductors, means for connecting the remote ends of said first pair of

conductors to the corresponding remote ends of said second pair of conductors so that corresponding conductors of each pair are effectively energized that radio frequency energy from said transmission line in a series relationship, each of said pair of conductors being of a length including at least one-half the length of the operating wave, whereby there is minimized the existence of reflected waves on said transmission line which might disturb the radiation characteristics of said antenna conductors.

4. A directional antenna comprising a pair of linear conductors, said conductors being disposed at an angle other than 180° with respect to each other in a single plane, a transmission line connected to the adjacent ends of said pair of conductors, a second pair of conductors similar and parallel to said first pair of conductors and so closely spaced therefrom that the mutual impedance between said conductors is substantially equal to the impedance of one of said conductors, means for connecting the remote ends of said first pair of conductors to the corresponding remote ends of said second pair of conductors, the adjacent ends of said second pair of conductors being connected together so that corresponding conductors of each pair are effectively energized that radio frequency energy from said transmission line in a series relationship, each of said conductors having a length equal to an odd multiple of an eighth of the length of the operating wave, whereby there is minimized the existence of reflected waves on said transmission line which might disturb the radiation characteristics of said antenna conductors.

5. A directional antenna comprising a pair of linear conductors, said conductors being disposed at an angle other than 180° with respect to each other in a single horizontal plane, a transmission line connected to the adjacent ends of said pair of conductors, a second pair of conductors similar and parallel to said first pair of conductors and so closely spaced therefrom that the mutual impedance between said conductors is substantially equal to the impedance of one of said conductors, means for connecting the remote ends of said first pair of conductors to the corresponding remote ends of said second pair of conductors so that corresponding conductors of each pair are effectively energized that radio frequency energy from said transmission line in a series relationship, the adjacent ends of said second pair of conductors being connected together, each of said conductors having a length equal to an odd multiple of an eighth of the length of the operating wave, whereby there is minimized the existence of reflected waves on said transmission line which might disturb the radiation characteristics of said antenna conductors.

6. A directional antenna comprising a pair of linear conductors, said conductors being disposed at an angle other than 180° with respect to each other in a single horizontal plane, a transmission line connected to the adjacent ends of said pair of conductors, a second pair of conductors similar and parallel to said first pair of conductors and closely spaced therefrom in the same horizontal plane, the spacing being such that the mutual impedance between said conductors is substantially equal to the impedance of one of

said conductors, means for connecting the remote ends of said first pair of conductors to the corresponding remote ends of said second pair of conductors so that corresponding conductors of each pair are effectively energized that radio frequency energy from said transmission line in a series relationship, the adjacent ends of said second pair of conductors being connected together, each of said conductors having a length equal to an odd multiple of an eighth of the length of the operating wave, whereby there is minimized the existence of reflected waves on said transmission line which might disturb the radiation characteristics of said antenna conductors.

7. A directional antenna comprising a pair of linear conductors, said conductors being disposed at an angle other than 180° with respect to each other and being located in a single horizontal plane, there being a predetermined relation between the lengths of the conductors and the included angle, a transmission line connected to the adjacent ends of said pair of conductors, a second pair of conductors similar and parallel to said first pair of conductors and closely spaced therefrom in the same horizontal plane, the spacing being such that the mutual impedance between said conductors is substantially equal to the impedance of one of said conductors, means for connecting the remote ends of said first pair of conductors to the corresponding remote ends of said second pair of conductors so that corresponding conductors of each pair are effectively energized that radio frequency energy from said transmission line in a series relationship, each of said conductors having a length equal to one-half the length of the operating wave, whereby there is minimized the existence of reflected waves on said transmission line which might disturb the radiation characteristics of said antenna conductors.

8. A directional antenna comprising a pair of linear conductors, said conductors being disposed at an angle other than 180° with respect to each other and being located in a single horizontal plane, there being a predetermined relation between the lengths of the conductors and the included angle, a transmission line connected to the adjacent ends of said pair of conductors, a second pair of conductors similar and closely spaced therefrom in the same horizontal plane, the spacing being such that the mutual impedance between said conductors is substantially equal to the impedance of one of said conductors, means for connecting the remote ends of said first pair of conductors to the corresponding remote ends of said second pair of conductors so that corresponding conductors of each pair are effectively energized that radio frequency energy from said transmission line in a series relationship, the adjacent ends of said second pair of conductors being connected together through a resistance, each of said conductors being of a length including at least one-half the length of the operating wave, whereby there is minimized the existence of reflected waves on said transmission line which might disturb the radiation characteristics of said antenna conductors.
